Joseph Crail Warren, Ohio

6543X

Sellers' Patent

The invention referred to in these Sellers' Patent and making part of the same containing a description in the words of the late Joseph Crail himself of his improvement in the Butter Churn.

I call when these presents shall come. Be it known that Joseph Crail of Warren in the County of Franklin and State of Ohio have invented a new and useful improvement to the Butter Churn and that the following is a full and exact description of the construction and operation of the said machine as invented or improved by me. I witness.

The body of the Churn is a square box composed of four sides and a bottom. The sides of the Churn are made of boards of one and one fourth inch in thickness halved and nailed together at the corners the grain of the board running, respectively. The height of the said sides is twenty three inches and the other two sides thirty inches. The bottom is let into a groove in the sides two inches above the lower end. The lid is of two pieces and let into the top of the Churn one inch below the top of the four sides. The depth of the Churn in the clear is twice the width, the width ten inches. A shaft ten and a half inches in diameter passes through the center of the Churn vertically and stays in a groove or joint, on the lower end which is let into the bottom of the Churn. A pin on the top end of the shaft stays in a pair of timber three inches in breadth and one and a half in thickness which passes over the center of the Churn and is fastened at each end by leaves let into the tops of the four sides, six pounds or rods three eights of an inch in diameter and ten inches in length and pass through the shaft at the lower end, the first one inch from the bottom and the last six inches which the first one and a half inches above the first and is in alternately each turned or sprung the one next to it at right angles and one half inch from it. The body of the Churn is prepared made of beech wood with one Marvin back which is placed some inches above the top of the Churn. The shaft of the Churn is four feet long, turned by a box and shaft or case. The box above and

55/1851 (6543)

half feet long the end of paper once round ~~round~~ the shaft between the two
of the chain and the crop piece which is led into the long narrow slot of the chain
and is made fast to each end of the box. The motion is communicated to the
shaft by hand.

What I claim as particularly new and of my own invention
is the manner of moving the shaft (or blower) by a ^{long} thin and strap
fitting.
